US0D1108749S

(12) **United States Design Patent** (10) Patent No.: **US D1,108,749 S**
(45) Date of Patent: ** Jan. 6, 2026

(54) **CLEANING ROBOT**

(71) Applicant: **Beijing Roborock Technology Co., Ltd.**, Beijing (CN)

(72) Inventors: **Kun Jiang**, Beijing (CN); **Fanwei Meng**, Beijing (CN); **Zechen Yu**, Beijing (CN)

(73) Assignee: **Beijing Roborock Technology Co., Ltd.**, Beijing (CN)

(**) Term: **15 Years**

(21) Appl. No.: **35/522,010**

(22) Filed: **Jul. 26, 2024**

(80) **Hague Agreement Data**

Int. Filing Date: **Jul. 26, 2024**

Int. Reg. No.: **DM/239311**

Int. Reg. Date: **Jul. 26, 2024**

Int. Reg. Pub. Date: **Aug. 23, 2024**

(30) **Foreign Application Priority Data**

Feb. 5, 2024 (CN) 202430080077.9

(51) LOC (15) Cl. 15-05

(57) **CLAIM**

The ornamental design for a cleaning robot as shown and described.

DESCRIPTION

1. Cleaning robot
2. Cleaning robot
- 1.1 : Front
- 1.2 : Back
- 1.3 : Left
- 1.4 : Right
- 1.5 : Top
- 1.6 : Bottom
- 1.7 : Perspective
- 1.8 : Perspective
- 1.9 : Front
- 1.10 : Back
- 1.11 : Left
- 1.12 : Right
- 1.13 : Top
- 1.14 : Bottom
- 1.15 : Perspective
- 1.16 : Perspective
- 2.1 : Front

(Continued)

2.2 : Back
2.3 : Left
2.4 : Right
2.5 : Top
2.6 : Bottom
2.7 : Perspective
2.8 : Perspective
2.9 : Front
2.10 : Back
2.11 : Left
2.12 : Right
2.13 : Top
2.14 : Bottom
2.15 : Perspective
2.16 : Perspective

1.1 to 1.16 show a first cleaning robot, wherein 1.9 to 1.16 show a variation state that the side brush and one of the mops are each shifted to an outward position, respectively; 2.1 to 2.16 show a second cleaning robot, wherein 2.9 to 2.16 show a variation state that the side brush and one of the mops are each shifted to an outward position.
